FLASHER SWITCH

Luther R. Harmon, Chicago, Ill., assignor of thirty-seven and one-half per cent to Fred Burt, thirty-seven and one-half per cent to William D. Lloyd, and twenty-five per cent to Patterson Manufacturing Company, a corporation of Illinois

Application November 19, 1942, Serial No. 466,218

6 Claims. (Cl. 200—113)

This invention relates to a flasher switch and concerns itself primarily with a snap action member that is so constructed, mounted and operated as to spring quickly and clearly away from an engaged contact without causing burning or injurious sparking.

In flashing systems, it is necessary to use an intermittently operated switch for making and breaking the circuit. If the switch contacts do not separate quickly and clearly, there is apt to be much sparking that soon burns the contacts.

To prevent burning of the contacts, it has heretofore been more or less the practice to use platinum in the construction of the contacts. Platinum however is very costly and greatly increases the cost of such switches.

This invention is designed to overcome the above noted objections in the construction of a snap switch in which the contacts make a quick and clear separation without any objectionable sparking and burning whereby the use of costly materials such as platinum may be avoided.

The invention comprises the novel structure and combinations hereinafter described and more particularly pointed out and defined in the appended claims.

In the accompanying drawing which illustrates a preferred form of this invention and in which similar reference numerals refer to similar features in the different views:

Fig. 1 is an elevational view of a flasher switch involving this invention.

Fig. 2 is an enlarged top plan view of the same.

Fig. 3 is an enlarged sectional view taken upon the line 3—3 of Fig. 2 looking in the direction of the arrows.

Fig. 4 is an enlarged sectional view taken upon the line 4—4 of Fig. 2 looking in the direction of the arrows.

Fig. 5 is a diagrammatic view illustrating the wiring diagram.

In referring now to the drawing, it will be observed that the switch mechanism is mounted upon an insulated base 1 from which extend a pair of substantially parallel metal frame members 2 and 3 which are inwardly offset at their upper portions as indicated at 2a and 3a to provide a somewhat restricted space therebetween. These frame members are shown as extending in vertical planes though they may be made to extend in other suitable planes and they are preferably integral with a base portion 4 secured to the base 1 by a conducting rivet 5 which also secures a terminal post 6 for the flashing lights to which reference will later be made.

Between the restricted portions of the frame, there is pivoted a metal lever 7 of conductive material. This lever 7 is of the bell crank variety having one arm 7a extending at substantially a right angle to the other arm 7b with the pivot 8 of the lever extending thru the elbow of the lever and into the frame members. A resistance wire 9 is attached at one end to the outer end of arm 7a; the other end of the wire is attached to a spring bracket 10 fastened to the base 1. It will be noted that the bracket 10 has a foot 10a secured to the base 1 by an electrical conducting rivet 11 which extends thru the base and secures a terminal post 12 upon the bottom of the base. The bracket 10 also has an upstanding portion 10b thru which a screw 13 extends that is threaded in the base 1 and is adjustable for varying the elevation of the upstanding portion 10b of the bracket 10 for loosening or tightening the resistance wire 9.

The arm 7b of the lever 7 terminates in a bifurcation 14. One side or wall of this bifurcation has a contact point 15 while the opposite side or wall is insulated as indicated at 16.

A spring-like or yieldable snap-switch member 17 preferably made of beryllium copper has a free end or tail 17a extending into the bifurcation 14 between the contact 15 and the insulation 16. This snap switch member which is a good electrical conductor has an attaching portion 17b secured to the base 1 by the rivet 5 so as to conduct the current to the post 6. Spaced inwardly or downwardly from the free end 17a of the switch member, there is a second securing means

30 which consists of a pin or rod 18 attached to said switch member and extending thru the frame members 2 and 3 and projecting slightly therebeyond for a purpose that will later appear. This spring-like switch member 17 is adapted to be bowed in two directions between its attached points 17b and 18 for engaging and disengaging an adjustable contact in the form of a screw 19. The screw 19 is mounted in the upper end portion of an electrical conducting bracket 20 (Fig. 45) which may be integral with the base 21 of an upstanding bracket 22 having a curved terminal 23. The base of said bracket 22 is secured to the base 1 by a rivet 24.

Spaced from the bracket 22, there is shown a solenoid or coil 25 supported upon the base 1 for controlling a pilot light. An electrical conductor in the form of a rod 26 extends thru the coil 25 and thru the base 1. A pilot light terminal 27 is attached to the lower end of said rod 26 and rests against the base 1.

Current is adapted to be conducted to the rod 26 from a switch plate 28 which is slotted and mounted over the curved portion 23 of the bracket 22 which has arresting shoulders 29 for supporting said plate. A coil spring 30 secured at one end to the bracket 22 and at its other end to the tail of plate 28, which it will be noted extends beyond the bracket, serves to normally hold the plate 28 against the end of the curved portion 23 of the bracket as shown in Fig. 4 in switch open position.

When the resistance wire 9 elongates thru the heating effect of the current passing therethrough, it will slacken its pull upon the lever 7 and allow spring 31 to move the lever arm 7b to the right as viewed in Fig. 3 and exert pressure against the tail 17a of the switch member 17 for a purpose that will later appear.

The spring 31 consists of a pair of parallel arms 31a anchored at their ends in the standards 2 and 3 as indicated at 32; the upper ends of the arms being integrally connected by a cross piece or bridge 31b which presses against the arm 7b of lever 7 as shown in Figs. 1 and 3. For this purpose, the standards are cut out as indicated at 33. To maintain the arms 31a under tension, they are positioned back of the projecting ends of the pin 18 as shown in Fig. 1.

An insulated wire 34 constitutes the coil 25; one end of the coil being in contact with the bracket 10 thru the rivet 11; the other end being connected to the base 21 of the bracket 22 as indicated at 35.

The current from any suitable source is led to the post 12 (Fig. 1). From the post 12, the current may flow thru either of two paths depending upon the position of the switch member 17. If the switch member is out of contact with the screw 19 as shown in dotted lines in Fig. 3, the current will flow thru bracket 10, resistance wire 9, lever 7 and switch member 17 to post 6 which is connected to the flashing circuit which however will be ineffective due to the resistance; the current returning from the light to the source of energy.

When the resistance wire 9 becomes heated thru the current passing therethrough, it will elongate as previously set forth and allow spring 31 to exert pressure against the arm 7b of lever 7 and cause said arm to exert pressure against the tail 17a of the switch member 17 and cause said switch member 17 to bow and spring to full line position into contact with contact screw 19. When the switch member 17 is in full line, the current will flow from post 12 thru wire 34, to bracket 20, contact screw 19 and switch member 17. From switch member 17, the current will flow thru rivet 5 to the flashing light circuit which will now be effective due to the stronger current. Part of the current from the wire 34 will pass thru the bracket 22 and switch plate 28 which will have been attracted against the rod 26 and thru said rod for illuminating a pilot light as will later more fully appear from the description of Fig. 5.

When the thermo-resistance wire 9 cools while no current is passing therethrough, it will contract and swing the insulated wall 15 of the bifurcation against the tail 17a of the switch member 17 and cause the same to bow toward the right as viewed in Fig. 3 and then snap away from contact 19 very quickly and clearly without any injurious sparking or burning of the contacts 75

and the lighting circuit will be broken and the resistance will again be established.

The operation can be more readily understood from a description of the wiring diagram shown in Fig. 5. In this figure, it will be noted that the flashing light 37 is connected with the switch member 17 above the lower terminal for convenience and that the current from the battery 38 will flow thru ground to point 12. Now if the switch 17 is open, the current from the battery 38 will flow thru wire 41, ground, and wire 42 to point 12, resistance wire 9, lever 7, switch member 17 and wire 43 to flasher light 37 which however will be ineffective due to the resistance. When wire 9 cools, the switch member 17 will be snapped to closed position as shown in full lines and the current from point 12 will now flow thru wire 34, solenoid 25, wire 44 to post 18, switch member 17 and back to the battery. The flashing light 37 will now be illuminated and incidently, the solenoid 25 will complete the circuit to the pilot light 45.

The reason for the quick and clear snap action of the switch member 17 away from contact 19 arises primarily from the fact that the contact 19 is located some distance beyond the longitudinal center of the switch member 17 and beyond the part that bows. As a result, when pressure is applied to the tail 17a of the switch member 17 when it is in full line position, the switch member will be put under strain that will cause the bowed part to gradually move to the right (Fig. 3) in advance of any movement away from the contact 19. In other words, the action is such that the movement of the switch member 17 away from contact 19 will be delayed until the bowed part has been brought substantially to the snapping over position. Thus when the snap action occurs, the switch member 17 will quickly and clearly snap away from contact 19 and avoid injurious sparking and burning.

It will be appreciated that if the contact 19 were located at the bowed portion of the spring switch, there would be a gradual and hesitant movement of such switch away from contact 19 during the time that tension was being built up in such switch member with the result that sparking and burning occur.

From the foregoing, it will be evident that a novel switch admirably adapted for a flasher has been invented that avoids injurious sparking and burning during the making and breaking of circuits. It will be appreciated that overcoming the hesitant action of contacts in separating thru the building up of energy in the snap switch member so as to obtain a quick and clear break produces a highly desirable new result in such switches.

I am aware that many changes may be made and various details of construction modified without departing from the principles of this invention so I do not propose limiting the patent granted thereon otherwise than necessitated by the prior art and appended claims.

I claim as my invention:

1. In a switch of the class described, an insulated base, a frame extending from said base, a snap-action switch member secured at one end to said base, a pivot pin connecting said member with said frame at a point spaced from the other end of said member leaving a tail piece beyond said pivot point, an electrical conducting lever having a bifurcation receiving said tail piece, one wall of said bifurcation being insu-

lated, thermoresponsive resistance means for moving said lever in one direction for exerting pressure against said tail piece, yielding means for moving said lever in the other direction for exerting pressure on said tail piece, said switch member being bowable between its supports and co-operating contacts, one located on said switch member beyond the greatest flexible portion of the bowable portion for the purpose set forth.

2. In a switch of the class described, a stationary contact, a yieldable snap-action switch member having a single bowable portion and a contact located beyond the greatest flexible portion of the bowable portion adapted for engaging said stationary contact, means for anchoring one end of said switch member, pivot means for supporting said switch member adjacent its other end, a conducting lever having a bifurcation engaging said switch member, said bifurcation having insulation upon one side and thermoresponsive means connected to said lever for controlling the movements thereof.

3. In a switch of the class described, an insulated base, a conducting bracket extending from said base, a contact carried by said bracket, a yieldable snap action switch member rigidly secured to said base adjacent said bracket adapted for engaging and disengaging said contact, said switch member having a bowable portion beyond said contact, means for supporting said switch member beyond said bowable portion, a conducting lever having a bifurcation engaging said switch member, one side of said bifurcation being insulated and thermoresponsive means for controlling said lever.

4. In a flasher switch, a stationary contact, a bowable snap action switch member having a contact adapted for engaging and disengaging said stationary contact, means for anchoring said switch member adjacent one end, pivot means for supporting said switch member adjacent the other end, said switch member having a bowable portion between said contact and

5 pivot means and thermoresponsive means for initiating movement of said switch member for moving the same to substantially snap action position before causing separation of said contacts from engaged position, said initiating means including a member serving as an electrical conductor to said switch member in one position and being insulated from said switch member in another position.

10 5. In a flasher switch, a stationary contact, a snap action switch member having a contact for engaging said stationary contact, means for anchoring one end of said switch member, means for supporting said switch member adjacent the other end, said switch member having a bowable portion spaced in a longitudinal direction from said contacts, a conducting lever having a bifurcation engaging said switch member and thermoresponsive means for initiating movement of said switch member to substantially snap action position before causing separation of said contacts from engaged position, said lever serving as a conductor to said switch member in one position and being insulated therefrom in another position.

15 6. In a switch of the character described, a stationary contact, a snap action switch member having a contact adapted for engagement with and disengagement from said stationary contact, means for supporting said switch member at spaced points, said switch member having a single bowable portion sufficiently removed from said contacts in a longitudinal direction for movement to snap action position before separation of said contacts from an engaged position, and means including a thermoresponsive element for initiating movement of said switch member, said means also including a lever having a bifurcation for engaging said switch member and having one side wall of said bifurcation insulated.
